UNITED STATES PATENT OFFICE.

ALFRED LESSIG, OF BROOKLYN, NEW YORK.

DESIGN FOR AN ADVERTISING NOVELTY.

45,233.

Specification for Design.

Patented Feb. 10, 1914.

Application filed September 9, 1913. Serial No. 788,972. Term of patent 3½ years.

To all whom it may concern:

Be it known that I, ALFRED LESSIG, a citizen of the United States, residing in Brooklyn, in the county of Kings and State of New York, have invented a new, original, and ornamental Design for an Advertising Novelty, of which the following is a specification, reference being had to the accompanying drawings, forming part thereof.

Figure 1 is a perspective view of the de-

vice showing my new design. Fig. 2 is a plan view of the same, and Fig. 3 is a side elevation thereof.

I claim:

The ornamental design for an advertising novelty as shown.

ALFRED LESSIG.
